UNITED STATES PATENT OFFICE.

HERBERT H. RUSSELL, OF NEW HAVEN, CONNECTICUT, ASSIGNOR TO THE GREIST MANUFACTURING COMPANY, A CORPORATION OF CONNECTICUT.

SEWING-MACHINE RUFFLER.

1,392,970.

Specification of Letters Patent. Patented Oct. 11, 1921.

Application filed January 6, 1921. Serial No. 435,303.

To all whom it may concern:

Be it known that I, HERBERT H. RUSSELL, a citizen of the United States, residing at New Haven, in the county of New Haven 5 and State of Connecticut, have invented or discovered certain new and useful Improvements in Sewing-Machine Rufflers, of which the following is a specification, reference being had therein to the accompanying 10 drawing.

This invention relates to an improvement on the sewing machine ruffler covered by U. S. Patent No. 1,261,628, and has for its 15 object to provide improved means for preventing backward rotation of a ratchet wheel employed in a five-stitch ruffler.

In the ruffler constructed in accordance with said patent a friction spring for preventing backward movement of the ratchet 20 wheel has been interposed between the ratchet wheel and the pendulous lever from which the ruffling blade is operated, and as the said spring presses equally against the ratchet wheel and the pendulous lever, forcing 25 said lever toward the operating lever, the action of these parts has been objectionably stiff owing to the resulting friction, particularly when straight ruffling was being done, that is, when a forward movement was 30 imparted to the ruffling blade at each stitch. The present improvement comprises a thin plate spring having a turned-over lip between which and the body of the spring the ratchet wheel works, so that the ratchet 35 wheel is clasped on both sides near its outer edge by said spring, and thus the friction induced by said spring is practically on the ratchet wheel only, and the pendulous and the operating levers are greatly relieved from 40 the friction to which they have heretofore been subjected in rufflers of this kind.

In the accompanying drawing Figure 1 is a side view of a ruffler embodying the present improvement. Fig. 2 is a plan view 45 of the same, and Figs. 3 and 4 are detail views of the ratchet wheel and its friction spring.

Referring to the drawing, 12 denotes the body of the frame of the ruffler which is 50 preferably provided with an integral attaching portion or shank 13 by which it may be secured to the presser bar of a sewing machine, in substitution of an ordinary presser foot. The forked operating lever 14, which 55 is adapted to engage a pin or stud on the

needle-bar of the sewing machine, is pivotally mounted on a stud or pin 15 riveted or otherwise permanently attached to an upright portion of the frame 12. Also pivotally mounted on said stud or pin 15 is a pendulous or secondary lever 16 to the lower end of which the ruffling blade carrier 17 is jointed, the said lever 16 being provided at its top with a shoulder 18. The ruffling blade 17^a is attached to the carrier 17 as 60 usual. A ratchet wheel 19, having shallow notches 20, affording short radial teeth, and two deeper notches 21, affording longer radial teeth, is mounted for rotation on the stud or pin 15. 65

The operating lever 14 is constructed with a bent-over lip 22 to which is attached a pin or rivet 23 which serves as a pivot for a shiftable pawl lever 24 carrying a pawl 25 preferably formed integral with said lever 70 and adapted to engage the teeth of the ratchet wheel 19 and the shoulder 18 on the pendulous lever 16 when five-stitch ruffling is to be done; or the said lever may be shifted laterally for the purpose of disengaging 75 the pawl 25 from the ratchet wheel when plain ruffling is to be done, or when the ruffling blade is to perform a forward movement at each stitch. The pawl lever 24 may be held in either of the two positions to 80 which it may be adjusted by a finger 32 engaging either of the openings 33 near the free end of the pawl lever 24, said pawl lever being pressed upon by a spring 35 against the stress of which the free end of said pawl 85 lever may be lifted when it is to be shifted from one position to another. 90

The ruffler thus far described is essentially the same in construction and operation as the ruffler of the said Patent No. 1,261,628, 95 varying only slightly in details. In the present improved ruffler a thin spring metal plate 26 is mounted on the pivot pin 15, said plate being interposed between the ratchet wheel 19 and the upper part of the pendulous lever 16, said plate having a bent-over lip 26^a which extends over the peripheral portion of the ratchet wheel 19 so that said ratchet wheel is frictionally engaged on both sides between the said lip and the body of 100 said spring. The said plate spring 26 is provided with a boss 26^b contacting with the lever 16 and with a depending finger 27 bent to extend through an opening 28 in the upright frame part 12 to prevent movement 105 110

of the plate with the ratchet wheel. By virtue of this construction the ratchet wheel will be frictionally held so that backward movement thereof when the operating lever 14 is performing its downward movements will be prevented, while at the same time the pendulous lever 16 and the operating lever 14 will be relieved of the friction due to the use of the forms of springs heretofore employed for preventing the backward movements of ratchet wheels in "five-stitch" rufflers, and the rufflers will work more freely or easily, relieving the sewing machine from running so hard as heretofore when operating rufflers of the class to which the present invention relates. The term "five stitch" as applied to rufflers of the class to which this invention relates is understood in the art as referring to rufflers in which the frequency of the movement of the ruffling blades is controlled so that they may make only a single ruffling stroke to several stitches of a sewing machine, either five stitches or more or less, these rufflers being capable of adjustment, by throwing the ratchet wheels out of operation, so as to

make a ruffling stroke at each stitch, in doing plain ruffling.

Having thus described my invention I claim and desire to secure by Letters Patent:

1. In a sewing machine ruffler, the combination with a ratchet-wheel by which the frequency of the movements of the ruffling blade is controlled, of a friction spring engaging both sides of said ratchet-wheel and serving to prevent backward movement thereof.

2. In a sewing machine ruffler, the combination with a ruffling blade and means, comprising a pendulous lever provided with a shoulder, for operating said ruffling blade, of a ratchet-wheel having deep and shallow notches, an operating lever, a pawl connected with said operating lever and serving to engage said shoulder and also to engage said ratchet wheel when desired, and a spring mounted contiguous to said ratchet wheel and having a turned-over part between which and the body of said spring said ratchet wheel works.

In testimony whereof I affix my signature.

HERBERT H. RUSSELL.
